(57) **CLAIM**

The ornamental design for a stroller having a carrier as shown and described.

DESCRIPTION

FIG. 1 is a top, front, right perspective view of a stroller having a carrier in accordance with our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom view thereof.

Broken lines represent portions of the stroller having a carrier that form no part of the claimed design.

1 Claim, 7 Drawing Sheets

It is certified that error appears in the above-identified patent and that said Letters Patent is hereby corrected as shown below:

In the Drawings

On Sheet 4/7 of the drawings, please replace FIG. 4 with the corrected FIG. 4 as shown on the attached drawing sheet.

On Sheet 5/7 of the drawings, please replace FIG. 5 with the corrected FIG. 5 as shown on the attached drawing sheet.

Signed and Sealed this
